(57) **CLAIM**

The ornamental design for a dental capsule, as shown and described.

DESCRIPTION

FIG. 1 is a perspective view showing the new design for a dental capsule.

FIG. 2 is a right view thereof;

FIG. 3 is a left view thereof;

FIG. 4 is a top view thereof;

FIG. 5 is a bottom view thereof;

FIG. 6 is a front view thereof; and,

FIG. 7 is a back view thereof.

The broken lined showing portions of a dental capsule are included for illustrating environmental structure and form no part of the claimed design.
